US00D796197S

(12) **United States Design Patent** (10) **Patent No.:** **US D796,197 S**
Cornelius (45) **Date of Patent:** **** Sep. 5, 2017**

(54) **BAG**

(71) Applicant: **SharkNinja Operating LLC**, Newton, MA (US)

(72) Inventor: **Leanna Cornelius**, Acton, MA (US)

(73) Assignee: **SHARKNINJA OPERATING LLC**, Newton, ME (US)

(**) Term: **15 Years**

(21) Appl. No.: **29/566,101**

(22) Filed: **May 26, 2016**

(51) LOC (10) Cl. **03-01**

(52) U.S. Cl.

USPC **D3/276**; D3/900

(57) **CLAIM**

The ornamental design for a bag, as shown and described.

DESCRIPTION

FIG. 1 is a perspective view of a bag in accordance with my design;

FIG. 2 is a front view of the bag in accordance with my design;

FIG. 3 is a back view of the bag in accordance with my design;

FIG. 4 is a first side view of the bag in accordance with my design;

FIG. 5 is a second side elevation view of the bag in accordance with my design;

FIG. 6 is a top view of the bag in accordance with my design; and,

FIG. 7 is a bottom view of the bag in accordance with my design.

(Continued)

The broken lines illustrate portions of the bag that form no part of the claimed design.

1 Claim, 5 Drawing Sheets
